UNITED STATES PATENT OFFICE.

ROBERT J. POMPLIN, OF NEWPORT, NORTH DAKOTA.

PELT-STRETCHER.

1,099,394.

Specification of Letters Patent.

Patented June 9, 1914.

Application filed February 14, 1914. Serial No. 818,764.

To all whom it may concern:

Be it known that I, ROBERT J. POMPLIN, a citizen of the United States, residing at Newport, in the county of Burke and State 5 of North Dakota, have invented certain new and useful Improvements in Pelt-Stretchers, of which the following is a specification, reference being had to the accompanying drawings.

10 This invention relates to new and useful improvements in pelt stretchers.

The object of the present invention resides in the provision of a device for holding and stretching furs or pelts, which is provided 15 with means resiliently urging the pelt holding members to stretching position.

A further object of the invention resides in the provision of a pelt stretcher whereon the pelt may be readily secured and which permits 20 adjustments for various sizes of pelts.

With the above and other objects in view, the invention resides more fully in the novel combination, formation and arrangement of parts more fully hereinafter described, and particularly pointed out in the 25 claims hereto appended.

Reference is had to the accompanying drawings in which similar characters of reference designate corresponding parts 30 throughout the several views and wherein,

Figure 1 is a side elevation of my improved pelt stretcher. Fig. 2 is a central vertical sectional view therethrough. Fig. 3 is a sectional view on the line 3-3, of Fig. 1.

35 Referring more particularly to the accompanying drawings, the body portion of the device comprises a pair of side members 5 which have their upper ends curved together at 6 and secured by the hinge 7. To normally urge these side members apart so that the pelt held thereby will be stretched, a pair of bowed leaf springs 8 are provided and secured together by the rivet 9 at their bowed 40 portions. The ends of the springs are provided with longitudinal slots 10 and bolts 11 are passed through the slots and through the side members 5, whereby the springs are secured to the side members but are permitted free sliding movement with relation thereto 45 so that they may exert their resilient action.

To hold the lower portion of the pelt from sliding upwardly and to provide an adjustable holding member which will serve for various sizes of pelts, a plurality of blocks 55 12 are provided, each of which is slidably

mounted upon the lower end of the respective side member 5, by passing the side member through the longitudinal bore therein. The lower extremities of the side members are laterally directed as at 13 and feed 60 screws 14 are slidably passed through these laterally directed portions and have threaded engagement with the blocks 12. The outer ends of the feed screws are provided with enlarged heads 15 which prevent them 65 from passing through the laterally directing portions 13. Carried by the sides and ends of the blocks 12, are hooks 16.

In operation the pelt is engaged over the hinged end portion of the stretcher and has 70 its other end engaged by the hooks 16. The feed screws are then rotated to draw the blocks 12 downwardly and stretch the pelt longitudinally to any desired degree. At the same time the springs stretch the pelt 75 laterally by forcing the side members 5 apart.

From the foregoing it is observed that a comparatively simple device has been provided which may be easily operated and 80 which is efficient and durable in use, under all conditions.

Having thus described this invention what is claimed is:—

1. A stretching frame comprising a pair 85 of side members, means resiliently urging said side members apart, blocks slidably mounted on the lower ends of the side members, and means rotatably mounted in the side members for adjusting said blocks longitudinally of the members. 90

2. A stretching frame comprising a pair of side bars, and bowed leaf springs connected at their central portions and having their opposite ends slidably engaged with 95 said bars.

3. A pelt stretcher comprising a pair of side members having hinged connection at their upper ends, means resiliently urging said members apart, the lower extremities of said members being directed inwardly, blocks slidably on the lower end portions of said members, feed screws passed through said inwardly directed extremities and threaded on the blocks, and hook means carried by said blocks for engaging the pelt. 100 105

4. A pelt stretcher comprising a pair of side members having hinged connection at their upper ends, bowed leaf springs connected at their central portions and provided 110

at their end portions with longitudinal slots, and bolts passed through said slots and secured in the side members.

5. A stretching frame comprising a pair of side bars, bowed leaf springs connected at their central portions and provided at their end portions with longitudinal slots, bolts disposed through said slots into the

side bars, and members slidably mounted on one end of said side bars.

In testimony whereof I hereunto affix my signature in the presence of two witnesses.

ROBERT J. POMPLIN.
